UNITED STATES PATENT OFFICE

2,546,743

ELECTRICALLY HEATED DEICING SHINGLE

Joseph L. Harrison, Wallace, Idaho

Application September 8, 1949, Serial No. 114,617

5 Claims. (Cl. 219—19)

1

This invention relates to heated shingles positioned particularly along the eaves of a roof where snow melted by heat from the interior of the roof causes accumulations of ice on the eaves, and in particular the invention relates to shingles positioned under this accumulation or bank of ice in which electric heating elements are incorporated in the shingles to provide heat for melting the ice.

The purpose of this invention is to provide means for incorporating electric heating elements in shingles whereby heat may be supplied to the shingles when ice accumulates thereon.

Accumulations of ice on the eaves of a roof cause water from rain or melted snow to back up and leak through cracks or openings through the roof and efforts to remove ice accumulations on the eaves of a roof involve extreme hazards as ice only accumulates in extremely cold weather and at this time the elements are not favorable for roof climbing. With this thought in mind this invention contemplates electrically heated shingles that may be substituted for the usual shingles on the eaves of a roof and with these shingles connected to a suitable source of current supply the shingles are readily heated by turning on a switch that may be located at a remote point.

The object of this invention is, therefore, to provide means for incorporating electric heating elements in shingles so that the shingles may be used in the usual manner and particularly on the eaves of a roof.

Another object of the invention is to provide means for incorporating electric heating elements in shingles in which the shingles may readily be substituted for shingles now in use.

A further object of the invention is to provide electrically heated shingles which are of a simple and economical construction.

With these and other objects and advantages in view the invention embodies a composition shingle with electric heating elements embedded in the lower edge and with continuous circuits connecting the electric elements to a source of current supply.

Other features and advantages of the invention will appear from the following description taken in connection with the drawings wherein:

Figure 1 is a plan view showing a plurality of shingles with a wiring diagram in connection therewith and with parts of the shingles broken away showing electric heating elements incorporated in the shingles.

Figure 2 is a cross section through the elec-

2

trically heated shingles being taken on line 2—2 of Figure 1.

Figure 3 is a plan view similar to that shown in Figure 1 illustrating a modification wherein the electric heating elements incorporated in the shingles are connected in parallel.

Figure 4 is a cross section through a shingle taken on line 4—4 of Figure 3 with the upper parts of the side sections of the shingle shown separated in dash lines to facilitate installing connecting wires through the shingles to the heating elements therein.

Referring now to the drawings wherein like reference characters denote corresponding parts the electrically heated shingle of this invention includes an under part or section 10, an upper part or section 11, heating elements 12 and leads 13 and 14 from a suitable source of current supply.

In the design shown in Figure 1 a shingle of the type having three on a strip, is illustrated and the shingle is formed with spaced vertically disposed slots 15 and 16 in the lower edge or section thereof that is exposed to the weather and with overhanging flanges or lips 17 and 18 on the end 20 of the upper edge or section thereof that is covered by the exposed section of a superimposed shingle and, therefore unexposed, and in manufacturing the shingles the electric heating elements 12 are incorporated in asbestos pads therein with the opposite terminals of the elements 12 connected by wires 19 and 20 to the leads 14 and 13, respectively. It will be appreciated that the shingles are manufactured with the wires 19 and 20 extended therefrom and these wires are connected to the supply lines 13 and 14 as the shingles are installed on a roof, or the like. To facilitate connecting the wires 19 and 20 the upper portions of the shingles may be separated until connections have been made to the wires 10 and 20.

It will be understood, however, that the shingles may also be made with both the upper and lower parts 10 and 11 secured together in the shop and the ends of the wires 19 and 20 may be provided with plugs or other means whereby the shingles may readily be attached to the power lines.

The shingle illustrated in Figure 1 is of the three-on-a-strip type with the slots 15 and 16 dividing the exposed ends of the shingles, and it will be understood that one or any number of shingles may be provided on a strip or as a single unit. With the shingles arranged in this manner the extended ends 17 and 18 overlap corresponding ends or lips of adjoining shingles

whereby a complete roof may readily be formed with the heated shingles or the shingles may be extended to the second layer or even a third or fourth layer of heated shingles may be used.

In the design shown in Figure 3 a shingle unit 21 having a lower panel 22 and an upper panel 24 is shown, and in this design individual heating elements 25 are connected to bus bars or wires 26 and 27 with one terminal of each of the heating elements connected to one of the wires whereby the elements are connected in parallel and the shingle may be cut or broken in half or separated at either of the slots 28 and 29 or at any suitable point. The ends of the wires 26 and 27 may be connected to power lines or any suitable source of current supply.

As hereinbefore stated the shingles may be manufactured of any suitable composition with the heating elements between the outer and inner parts and the upper parts may be extended outwardly as indicated by the dash lines 32 and 33 in Figure 4 and with these parts open as shown the wires 26 and 27 may readily be incorporated therein. After the wires are in place the upper parts of the shingles may be cemented together or held together by any suitable means.

With shingles of this type incorporated in the eaves of a roof current may be supplied to the heating elements in the shingles as ice accumulates on the eaves and the ice may, therefore, be readily removed.

These shingles may be incorporated in a roof below the usual shingles, or mounted upon the shingles, or the shingles may be removed and replaced with the improved electrically heated shingles.

The ends of the shingle, particularly as shown in Figure 3 are provided with extensions 30 and 31 similar to the extensions 17 and 18 of the patterns shown in Figure 1, which complete the pattern of the shingle.

It will be understood that other modifications may be made in the design and arrangement of the parts without departing from the spirit of the invention.

What is claimed is:

1. An electrically heated roofing shingle comprising an elongated composition slab divided substantially midway of the width thereof forming a lower exposed section and an upper unexposed section, an electric heating element positioned in the exposed area of the slab, and power supply connections extended from the slab and connected to opposite terminals of the heating element.

2. An electrically heated roofing shingle comprising an elongated composition slab divided substantially midway of the width thereof forming a lower exposed section and an upper unexposed section, an electric heating element incorporated in the exposed area of the slab, and power supply connections extended from the slab and connected to opposite terminals of the heating element, the lower portion or exposed area of said slab having spaced parallel slots extended inwardly from the lower edge thereof positioned between the heating elements and also having extended flanges on the ends of the upper un-

exposed section thereof, said extended flanges positioned to overlap corresponding flanges of adjoining shingles.

3. In an electrically heated roofing shingle, the combination which comprises an elongated rectangular shaped panel divided substantially midway of the width thereof forming a lower exposed section and an upper unexposed section, having spaced parallel slots extended inwardly from the lower edge of the exposed section thereof and having extensions at the ends of the unexposed section thereof, spaced electric heating elements embedded in the shingle and positioned in the said unexposed section, a pair of power lines extended through the unexposed section of the shingle and means connecting one terminal of each of the electric heating elements to one of the said power lines.

4. In an electrically heated roofing shingle, the combination which comprises a rectangular shaped panel divided substantially midway of the width thereof forming a lower exposed section and an upper unexposed section, and a plurality of spaced U-shaped loops of electric heating elements extended from a point substantially midway of the width of the panel to points spaced from the lower edge of the exposed section thereof and with the lower ends of the loops connected by cross members spaced from the lower edge of the unexposed section of the panel, the side members of said loops connected to adjacent side members of adjoining loops at the inner ends thereof.

5. In an electrically heated roofing shingle, the combination which comprises a rectangular shaped panel divided substantially midway of the width thereof forming a lower exposed section and an upper unexposed section, and a plurality of spaced U-shaped loops of electric heating elements extended from a point substantially midway of the width of the panel to points spaced from the lower edge of the exposed section of the panel and with the lower ends of the loops connected by cross members spaced from the edges of the exposed section of the panel, power supply lines extended through the unexposed section of the panel, and means connecting the sides of the said loops to the power supply lines, respectively.
